UNITED STATES PATENT OFFICE.

THEODORE P. BROWN, OF WORCESTER, MASSACHUSETTS.

PLAYER-PIANO.

1,363,306.

Specification of Letters Patent. Patented Dec. 28, 1920.

Application filed October 10, 1916. Serial No. 124,831.

To all whom it may concern:

Be it known that I, THEODORE P. BROWN, a citizen of the United States, residing at Worcester, in the county of Worcester and 5 Commonwealth of Massachusetts, have invented a new and useful Improvement in Player-Pianos, of which the following, together with the accompanying drawings, is a specification.

10 My invention relates to player pianos and particularly to music roll and tracker bar adjusting mechanisms.

15 The object of my invention is to provide a music roll adjusting mechanism whereby the music roll may be shifted longitudinally without changing its relation to the bearing members upon which it is rotatably supported. A further object of my invention is to provide a device for adjusting 20 the tracker bar, by means of which the music being played may be readily transposed.

In the accompanying drawings,

25 Figure 1 is a view in front elevation of the music roll box of a player piano embodying my invention.

Fig. 2 is an enlarged plan view of a portion of the shifting lever mechanism located in the bottom of the music roll box.

30 Fig. 3 is a diagrammatic view showing the parts of the music roll adjusting mechanism in its different operative positions, only those parts of the music roll box relating to this mechanism being shown.

35 Similar reference characters refer to similar parts in the different figures.

Referring to the drawings, the music roll box comprises side portions 3 and 4, a back portion 5 and a base 6. A takeup spool 7 is rotatably mounted between the side portions 40 3 and 4 and is driven in any well known manner by driving mechanism, not shown.

45 Music spool bearings 8 and 9 are rotatably mounted in the side wall portions 3 and 4 respectively, between which is supported a music spool 40, as shown in Fig. 3. The bearing 8 is provided with a reduced portion 8^a that extends through the wall 3 and a bracket 10 carried on the outside of the wall 3. A coiled spring 11 surrounds the reduced portion 8^a of the bearing 8 between the end of the bracket 10 and a shoulder formed on the bearing 8 at the end of the reduced portion 8^a. The spring 11 tends to move the bearing 8 toward the right. The 50 bearing 9 is provided with a reduced portion 9^a which extends through the wall 4 and a

bracket 15 carried by the wall 4. A lever 13 is pivotally mounted at 14 upon a projection of the bracket 15 and is provided at its upper end with a set screw 12 that is normally held in engagement with the end of the reduced portion 9^a of the shaft 9. 60

The lower end of the lever 13 is pivotally connected at 16 to a bar 17 which extends behind the roll box, as indicated in dotted lines, and is pivotally supported at its left hand end by a floating lever 18. The opening 18^a in the lever 18, through which the end of the bar 17 projects, is made somewhat larger than the end of the bar 17, 70 for a purpose to be hereinafter described. The upper end of the floating lever 18 is provided with an opening through which the reduced portion 8^a of the shaft 8 projects, the lever 18 being caused to move with 75 the shaft 8 by means of a cap or nut 19 carried at the end of the portion 8^a. The lower end of the floating lever 18 is pivotally connected at 20 to a link 21 that extends through the wall 3. The portion of the lever 18 above 80 the link 21 is held in engagement with a guide 22 by means of a resilient finger 22^a. The inner end of the link 21 is pivotally connected to a lever 23 which extends beneath an indicating dial 24 mounted at the front of 85 the roll box. The lever 23 is provided with a handle 25, by means of which it may be moved along the indicating dial about its point of pivotal support.

Having described the various parts of 90 the music roll adjusting mechanism, the operation thereof is as follows:—Assume that the parts occupy the positions shown in Fig. 2, with the music spool in its normal position and with the handle 25 of the lever 95 23 in its extreme right hand position. If it is desired to shift the position of the roll carried by the spool 40, the handle 25 is moved to the left, as shown in dotted lines, thus moving the lower end of the floating 100 lever 18 to the right. As this movement occurs, the lever 18 tends to turn about the end of the rod 17 as a pivot, so that the upper end of the lever engages the nut 19 and moves the shaft 8 to the left against 105 the action of the spring 11. At the same time as the lever 18 is moved about the end of the rod 17, the pressure tending to hold the end of the shaft 9 in engagement with the set screw 12 is relieved, and the rod 17 110 is free to move bodily to the right to cause the upper end of the lever 13 to move in

the direction of the shaft 9. The movement of the handle 25 to the left thus causes a combined turning and shifting movement of the floating lever 18, which results in the movement of the shafts 8 and 9 and the music spool 40 to the left through the action of the lever mechanism. It is obvious that the reverse action will occur if the handle 25 is moved to the right so that the 10 music spool may be shifted in either direction by the simultaneous movement of the shafts 8 and 9 without any possibility of misalignment of the spool due to the failure of the shafts to support the ends of the 15 spool.

The mechanism for adjustment of the tracker bar comprises a lever 26 pivotally mounted at 26^a and provided at one end with a handle 29 extending upwardly in front of the indicating dial 24. A link 27 is connected to the lever 26 at the point 28, and is connected at its other end to a lever 30 that is pivotally supported at 31 upon a bracket 32. A tracker bar 33 extending 25 between the walls 3 and 4 of the roll box is slidably mounted at its ends in brackets 36 and 37. The tracker bar 33 is provided at its left hand end with a rod 34 that is connected to the lever 30 by means of a 30 pin 35. The right hand end of the tracker bar 33 is provided with pins 38 to serve as additional bearings therefor. The bottom of the indicating dial 24 is provided with a plurality of teeth 39, between which 35 the lever is adapted to fit. The link 27 is preferably made of inherently resilient material, and its right hand end is bent downwardly to the point 28 where it is attached to the lever 26, so that the tendency for the 40 end of the bar to return to its normal position causes the lever to be held firmly between the teeth 39.

When it is desired to shift the tracker bar, the handle 29 is pushed downwardly 45 to clear the lever from the teeth 39 and thus allow the handle 29 to be moved either to the right or to the left to shift the tracker bar 33 through the movement of link 27 and the lever 30. By this means the music being played may be readily transposed.

While I have shown my invention in its simple and preferred form as applied to a specific type of music roll box for a player piano, it is not so limited but is susceptible 55 of various modifications within the scope of the appended claims.

I claim:—

1. In a player piano, music spool bearings slidably mounted in coaxial relation,

means for normally maintaining said bearings toward each other to support a music spool, and means coöperating with the ends of the bearings for simultaneously shifting said bearings in the same direction.

2. In a player piano, music spool bearings slidably mounted in coaxial relation, means for normally maintaining said bearings toward each other to support a music spool, and means coöperating with the ends of the bearings for simultaneously shifting 70 said bearings along their longitudinal axes, to change the position of the music spool.

3. In a player piano, music spool bearings slidably mounted in coaxial relation, a spring normally biasing one of said bearings toward the other for supporting a music spool, and means coöperating with the ends of said bearings for releasing the pressure on the spring-pressed bearing, and for simultaneously shifting the bearings 80 along their longitudinal axes in the same direction.

4. In a player piano, music spool bearings slidably mounted in coaxial relation, a spring normally biasing one of said bearings toward the other for supporting a music spool, levers coöperating with the ends of said bearings, and means for shifting the spring-pressed bearing against the pressure of the spring, the said levers being 90 so connected that the other bearing is simultaneously shifted in the same direction as the spring-pressed bearing.

5. In a player piano, music spool bearings slidably mounted in coaxial relation for supporting a music roll therebetween, a pair of levers engaging the ends of the bearings, and a link connecting said levers, whereby 95 said levers may be moved in unison to shift the music roll.

6. In a player piano, music spool bearings slidably mounted in coaxial relation for supporting a music roll therebetween, a pair of levers engaging the ends of the bearings, and a link connecting said levers, one of 105 said levers having a fixed pivot and the other lever having a floating pivot provided by the point of connection of said link, whereby said levers may be moved in unison to shift the music roll.

In testimony whereof I hereunto affix my signature in the presence of two witnesses.

THEODORE P. BROWN.
